PACKAGED MULTISHEET ARTICLE

Filed April 14, 1930

Witness:

Inventor,
Richard C. Beatty
George Bayard Jones & Abby.

UNITED STATES PATENT OFFICE

RICHARD C. BEATTY, OF CHICAGO, ILLINOIS

PACKAGED MULTISHEET ARTICLE

Application filed April 14, 1930. Serial No. 444,015.

This invention relates to improvements in packaged multi-sheet articles and method of packaging the same.

In preparing multi-sheet articles, such as 5 wall calendars, for mailing in mailing tubes, the current practice is to roll the articles from the upper ends where the sheets are fastened together and insert them in a stiff mailing tube, or wrap them in a mailing wrapper, 10 forming a flexible tube. This results in the free edges of the sheets being stepped back progressively from the inner to the outer sheet with the result that the sheets are frequently torn or otherwise damaged during 15 removal of the tube and also the sheets have a tendency to curl and the lower ends flutter loosely when removed from the tube and hung on the wall. The use of a mailing tube generally is preferred over mailing the articles 20 flat because the tube affords better protection and is less costly, the use of envelopes or wrapping paper generally requiring that a stiffening board be used to prevent damaging the article. Thus the initial cost of wrapping 25 is increased as well as postage.

One object of the present invention is to provide a double rolled multi-sheet article the 30 tendency of the sheets of which to creep is compensated for to prevent creasing, which article can be mailed in a tube and can be freed from its container with less likelihood of damaging the sheets and which when so removed will hang or lie practically flat, with 35 no fluttering or curling of loose edges.

A further object of the invention relates to the method of rolling the article for insertion in a mailing tube.

In the following specification, the term 40 tube is intended to cover either a stiff mailing tube, a wrapper, or other suitable container, and in like manner, wherever the term calendar is employed it will be so used for the sake of brevity and as a generic designation for any multi-sheet article adapted to be rolled 45 for mailing in such container, since it will be apparent from a consideration of the following specification and drawing that the invention may be employed in conjunction with multi-sheet articles generally, although at 50 present the most useful field of the invention

appears to be in connection with the mailing of calendars.

In the accompanying drawing,

Fig. 1 is a perspective view of multi-sheet 55 article, such as a calendar.

Fig. 2 is a vertical section taken on line 2—2 of Fig. 1.

Fig. 3 is an end view of a packaged article comprising the present invention.

Fig. 4 is a diagram illustrating the initial 60 stages in rolling the article for insertion in a mailing tube or other container.

In the drawing 10 indicates a multi-sheet 65 article or calendar the sheets of which are shown as secured at the top by a conventional metal binding strip 11. As it is advantageous to bind the sheets also at the bottom to cause them to hang flat on the wall after the calendar has been removed from the mailing tube or package, I have shown a number of wire 70 staples 12 for this purpose although it will be apparent that any other means for securing the edges together may be employed, such as a binder similar to the strip 11, or glue, or any binding means known to the art. 75

The binding of the sheets at the bottom has necessitated mailing the calendar unrolled, as in an envelope, since in rolling the sheets from one end only in the conventional manner the securing means prevents them from slipping 80 one upon the other progressively, with the result that some of the inner sheets will wrinkle and become creased.

However with the improved method of rolling the article as illustrated in Fig. 3 and 85 diagrammatically in Fig. 4, wrinkling and creasing of the inner sheets are avoided. As shown in the figures mentioned, the article is rolled from one end to approximately one-half its length and then rolled from the opposite end on the opposite face of the article. In making the first roll 13, the inner sheets of 90 that roll will creep or slip to some extent in front of the roll, but as the unrolled ends are secured, these sheets will rise in waves or bulge adjacent such ends.

Since the second roll 14 is made on the opposite face of the article, the bulged sheets will 95 form the outer layers of the second roll and the slack in those sheets will be taken up as 100

the second roll 14 approaches the first roll 13. The two rolls thus lie on opposite sides of the original plane of the article and each face of the sheet forms the inner wall or layer of one roll and the outer surface of the other roll.

5 The two rolls can then be inserted in a mailing tube 15, or other package or wrapping as illustrated in Fig. 3.

It will be noted that when the double roll 10 is inserted in the package, longitudinal spaces 16, 17 are provided along either of which a knife can be run for cutting the wrapper with less danger of damaging the article than where the same is rolled in the conventional manner. Where stiff mailing tubes are employed, the conventionally rolled articles are generally withdrawn from one end, but sometimes with considerable difficulty. But as will be obvious from Fig. 3, the double roll 15 can easily be removed by inserting the thumb and finger in the rolls to grasp the intermediate wall 18, whereupon the article can be removed without difficulty.

As mentioned above, each roll comprises 25 approximately one-half the length of the article, but in cases where the calendar sheets are secured in the form of a pad of less length than the back, the rolls will be so proportioned that each will comprise about one-half the 30 length of the calendar sheets, the upper part of the backing sheet being entirely in one of the rolls, for example, in case the calendar sheets are secured to the lower part of said backing.

35 What I claim is:

1. A multi-sheet article having the sheets secured together at opposite ends and adapted to be rolled upon itself from both said ends to form two connected rolls, one face of the 40 article forming the inner wall of one of said rolls and forming also the outer wall of the other roll.

2. A packaged multi-sheet article having the sheets secured together on two opposite 45 ends and rolled upon itself in opposite directions from both said ends to form a double roll approximately mid-way between said secured ends, and a tube surrounding said rolled article.

50 3. A packaged multi-sheet article having the sheets secured together on two opposite ends and rolled upon itself from both said ends to form two rolls disposed approximately mid-way between said secured ends, one face of said article being on the interior of one roll and also on the exterior of said other roll, and a tube into which said rolled article is inserted.

55 In testimony whereof, I have subscribed my name.

RICHARD C. BEATTY.
